Application August 14, 1939, Serial No. 290,088

10 Claims. (Cl. 179—170)

The present invention relates generally to improvements in signal current transmission systems of the type in which signal controlled switching circuits are provided for partially or completely blocking, under certain conditions, certain of the signal current channels included therein and, more particularly, to improvements in telephone substation circuits having incorporated therein coupled signal current channels for the transmission of incoming and outgoing signal currents.

In the usual telephone substation circuit, a hybrid system or antiside tone impedance network is provided for preventing signal currents developed during operation of the transmitter from being transmitted to the receiver and for preventing signal currents incoming over the line extending to the substation from being transmitted to the transmitter. In this type of arrangement one of the factors which determines the efficiency of the side tone suppression is the impedance of the talking circuit established by way of two connected subscribers' lines. This impedance is not the same for any two different connections and, accordingly, the hybrid system of each substation is usually balanced to provide maximum side tone suppression efficiency for average line conditions. In installations wherein amplification of the incoming and outgoing signal currents is required, the conditions of unbalance introduced into the substation circuit by the impedances of the lines over which an established connection extends may become intolerable. This is particularly true in substation installations provided in an exchange area where the subscribers' lines are of widely different lengths. In order to obviate or minimize the singing which may result due to unbalance of the substation circuit occasioned by unfavorable line conditions, signal controlled switching means may be provided in the substation circuit for selectively blocking the signal transmission channels when not in use. In the usual arrangement of this character the transmission channels are completely blocked when not in use. More particularly, during intervals when the transmitting means of the substation is being used to transmit outgoing signal currents, the incoming signal current channel is rendered completely inactive. Conversely, during those periods when signal currents are incoming to the substation, the transmitting channel is rendered completely inactive. An arrangement of this character prevents any interruption of a speech train being transmitted in one direction in response to sig-

nal currents transmitted in the opposite direction. In other words, conversation break-ins are positively prevented.

It is an object of the present invention, therefore, to provide improved telephone substation apparatus of the character described wherein the blocking of the signal current transmitting and receiving channels is accomplished in a simple and reliable manner and wherein the control circuits are arranged to permit conversation break-ins.

It is a further and more specific object of the invention to provide an improved transmission system particularly suited for use in telephone substation circuits of the character described wherein the incoming and outgoing signal current channels are normally active and the transmission efficiencies of the two channels are varied in opposite senses by varying the plate or anode impedances of electron discharge control tubes respectively coupled thereto in response to signal currents traversing either of the two channels.

It is another object of the invention to provide a signal transmission system of the character described wherein the signal current transmission efficiency or gain of each channel is varied inversely in accordance with the amplitude of signal currents impressed upon the input side thereof.

In each of the three illustrated embodiments of the invention there is provided a telephone substation circuit which is adapted to be connected to an associated line and comprises the usual transmitting and receiving means. The circuit also includes a transmission system which comprises a hybrid or antiside tone network, a first channel for transmitting signal currents from the transmitting means through the hybrid network to the associated line and a second channel for transmitting incoming signal currents from the hybrid network to the receiving means. Each of the two transmission channels has included therein a voltage divider comprising one leg serially included in the associated channel and a second leg shunting a portion of the channel. One leg of each of the two voltage dividers is bridged by an adjustable impedance in the form of the space current path of an associated electron discharge tube, whereby the signal current transmission efficiencies of the two channels are variable with variations in the output electrode impedances of the respective associated tubes. The control electrodes of the two tubes are normally biased to potentials such that

the associated channels are both active, a control circuit being provided for varying the control electrode potentials in response to signal currents traversing one of the channels so that the gain or signal current transmission efficiency of the one channel is substantially increased and the signal current transmission efficiency of the other channel is substantially decreased. In one embodiment of the invention, the control circuit further includes apparatus comprising one of the two control tubes for varying the transmission efficiency of the channel in use inversely in accordance with the amplitude of the signal input thereto, thus providing automatic gain control action. More particularly, automatic gain control is achieved by varying the bias on the control tube associated with the channel in use to vary the output electrode impedance thereof so that the transmission efficiency of the channel is changed inversely in accordance with the signal input thereto.

Further features of the invention pertain to the particular arrangement of circuit elements whereby the above-mentioned and additional operating features are attained.

The novel features believed to be characteristic of the invention are set forth with particularity in the appended claims. The invention, both as to its organization and method of operation, together with further objects and advantages thereof will best be understood by reference to the specification taken in connection with the accompanying drawings in which Figure 1 illustrates a substation circuit having incorporated therein certain of the features of the invention as briefly outlined above; Fig. 2 illustrates a modified form of the improved substation circuit; and Fig. 3 illustrates a modification of the circuit arrangement shown in Fig. 2.

Referring now more particularly to Fig. 1 of the drawings, the substation circuit there illustrated is adapted to be connected to a telephone line terminating at the terminals 100, which line may, for example, form a part of a conventional automatic or manual telephone system, in which case, the distant end thereof will terminate in a line circuit the character of which is determined by the character of the exchange. Briefly described, the substation circuit comprises a transmitter or microphone 101 and receiving means in the form of a loud speaker 102 which are adapted respectively to be coupled to an antiside tone impedance network including a hybrid coil 103 and a balancing circuit 104 by means of signal transmission channels 105 and 106. Preferably, the loud speaker 102 is of the well-known moving coil type having embodied therein a voice or signal current coil 107 which is adapted to be energized by incoming signal currents transmitted thereto through the hybrid coil 103 and over the transmission channel 106. The outgoing signal current channel 105 comprises a vacuum tube amplifier 108 arranged to deliver its output to two additional stages of amplification 109 and 110, the last of which is arranged to deliver its output to the hybrid system 103 through a coupling transformer 111. This channel further comprises a voltage divider in the form of a potentiometer resistor 112 having a nonadjustable leg 112a, serially included in the channel, and a second leg 112b, any portion of which may be bridged across the channel by manual adjustment of the tap 113. More specifically, the stage of amplification 109 comprises an electron discharge tube 114 of the well-known pentode type

which includes a cathode 115 and a control grid 116 coupled to the output circuit of the amplifier 108 by means of a resistance capacitance coupling network including a condenser 117 and a resistor 118. The amplifying stage 110 similarly comprises an electron discharge tube 119 having a cathode 120 and a control grid 121 coupled to the output electrodes of the preceding tube 114 through a resistance capacitance coupling network which includes the voltage dividing resistor 112, a condenser 121' and a load resistor 122. The output electrodes of the tube 119 are coupled to the outgoing signal current terminals of the hybrid system 103 through the coupling transformer 111. For the purpose of biasing the control grid 116 of the tube 114 negatively with respect to the associated cathode 115, there is included in the output circuit of this tube a cathode biasing resistor 122' which is shunted by a signal current by-pass condenser 123. Similarly, a cathode biasing circuit comprising a resistor 124 shunted by a by-pass condenser 125 is provided in the output circuit of the tube 119. Operating voltages are impressed upon the anode and screen electrodes of the two tubes 114 and 119 from a source of direct current, not shown, but having its positive terminal connected to the terminals marked +B. This source is by-passed for signal currents in the amplifier stages 109 and 110 by means of by-pass condensers 126 and 127, respectively.

The signal transmission channel 106 is coupled to the incoming signal current terminals of the hybrid system 103 through a coupling transformer 128 and includes a first stage of amplification 129 followed by a power amplifier unit 130. The channel 106 further comprises a voltage divider in the form of a potentiometer resistor 131 having a leg 131a serially included in the channel and a second leg 131b, any portion of which may be connected in shunt with the channel by manually adjusting the tap 132. More particularly, the amplifier stage 129 comprises an electron discharge tube 133 of the well-known pentode type which includes a control grid 134 and a cathode 135 coupled to the secondary winding of the transformer 128, and output electrodes including the cathode 135 and an anode 136 coupled to the input circuit of the power amplifier 130 through a resistance capacitance network which includes the potentiometer resistor 131, a condenser 137 and a load resistor 138. The positive terminal of the anode current supply source is connected to the anode 136 and the screen electrode of the tube 133 through the terminal marked +B, this source being by-passed for signal frequency currents through the provision of a shunt connected condenser 139. For the purpose of biasing the control grid 134 of the tube 133 to the proper negative potential with respect to the cathode 135, there is included in the output circuit of the tube a cathode biasing resistor 140 which is shunted by a by-pass condenser 141.

In order to control the signal transmission efficiencies of the two channels 105 and 106, two control circuits 142 and 143 are provided. Since these control circuits are in all respects identical, only the circuit 143 has been illustrated in detail. Briefly described, this circuit comprises an amplifier 144 having its input terminals coupled to the channel 105 at a point just preceding the amplifier stage 109 and its output terminals coupled through a transformer 145 to a rectifying circuit which includes a dry disk rectifier 146, preferably of the copper oxide type, and a load re-

sistor 147 shunted by a condenser 148. This rectifying circuit is coupled to the input electrodes of an electron discharge tube 149 which is arranged to act as a direct current amplifier. More particularly, a load resistor 150, shunted by a bypass condenser 151', is provided in the output circuit of the tube 149 and is connected so that the voltage developed thereacross is arranged to control the potentials respectively impressed upon the control electrodes of two electron discharge tubes 151 and 152. To this end, the voltage developed across the resistor 150 is impressed upon the control electrode of the tube 151 through a resistor 153 and upon the control electrode of the tube 152 through a resistor 154. The indicated control electrodes are normally biased to the desired negative potentials through the provision of small C batteries 155 and 156. The two tubes 151 and 152 are connected to control the gains or signal current transmission efficiencies of the two channels 106 and 105, respectively. More particularly, the output electrodes of the tube 151 are bridged across the shunt leg 131b of the voltage divider 131 through a direct current blocking condenser 157. The output electrodes of the control tube 152, on the other hand, are bridged across the series leg 112a of the voltage divider 112 through a pair of blocking condensers 158 and 159. In order effectively to isolate the output electrode impedances of the two tubes 151 and 152 anode current is delivered to these two tubes through high impedance iron core inductors 160 and 161. The output electrode impedance of the tube 152 is further isolated through the provision of a third high impedance iron core inductor 162 which is included in the cathode leg of the output circuit of this tube. The last-mentioned impedance element is chosen to present an extremely high impedance to signal currents, whereby the condenser 159 is prevented from effectively short-circuiting the shunt leg 112b of the voltage divider 112 insofar as signal currents traversing the channel 105 are concerned. This element is also constructed to have a very low direct current resistance whereby no substantial bias is impressed upon the cathode of the tube 152 due to the inclusion of the element in the cathode leg of the output circuit of this tube.

As indicated above, the two tubes 151 and 152 are arranged to control the transmission efficiencies of the signal current channels 106 and 105, respectively. Thus, the output electrode impedance, that is, the impedance between the anode and cathode of the tube 151 is connected in shunt with the shunt leg 131b of the voltage divider 131. Accordingly, if the output electrode impedance of the tube 151 is high, the equivalent value of this impedance as combined with that of the shunt leg 131b is relatively high so that a relatively small portion of the available signal voltage impressed across the outer terminals of the voltage divider 131 by the amplifier stage 129 appears across the series leg 131a thereof. Hence, a relatively large portion of the available signal voltage appears across the shunt leg 131b and is impressed across the input terminals of the power amplifier 130. Thus, the transmission efficiency of the channel 106 or the gain therethrough is relatively high when the output electrode impedance of the tube 151 as determined by the potential impressed upon the control electrode of this tube is high. When, however, this potential is adjusted or changed to lower the output electrode impedance of the tube 151, the

equivalent impedance formed by the combination of this impedance and the resistance of the shunt leg 131b is lowered to produce a corresponding increase in the signal voltage drop across the series leg 131a. As a consequence, a lesser percentage of the available signal voltage is impressed upon the input electrodes of the power amplifier 130. Thus, the gain or transmission efficiency of the channel 106 is reduced when the output electrode impedance of the tube 151 is decreased. Stated generally, the signal current transmission efficiency of the channel 106 is variable directly in accordance with variations in the output electrode impedance of the tube 151.

Since the output electrodes of the tube 152 are bridged across the series leg 112a of the voltage divider 112, the effect of changing this impedance is the exact reverse of that just described with reference to the tube 151. More particularly, if the output electrode impedance of the tube 152 is increased from a normal value to a higher value the equivalent impedance of this output electrode impedance as combined with the resistance of the leg 112a is increased, whereby the signal current flow through the shunt leg 112b of the voltage divider 112 is decreased to produce a corresponding decrease in the signal voltage impressed across the input electrodes of the amplifier tube 119. On the other hand, if the output electrode impedance of the tube 152 is decreased from a high value to a lower value, the signal current flow through the shunt leg 112b is increased to produce a corresponding increase in the percentage of the available signal voltage which is impressed across the input electrodes of the tube 119. Thus, when the output electrode impedance of the tube 152 is increased the gain or transmission efficiency of the channel 105 is decreased, whereas when the value of this impedance is decreased the gain or transmission efficiency of the channel 105 is increased. In other words, the signal current transmission efficiency of the channel 105 is variable inversely in accordance with variations in the output electrode impedance of the tube 152.

Normally, the two tubes 151 and 152 are biased to a point slightly above anode current cut-off so that the output electrode impedances thereof are relatively high. With the two tubes biased in this manner the transmission efficiencies of the two channels 105 and 106 may be changed at will by manually adjusting the taps 113 and 132 so that they are approximately equal or bear any desired ratio to each other. Preferably, however, the adjustment is such that both channels are normally capable of transmitting signal currents with reasonably good efficiency but are insufficient to permit local oscillation of the circuit even when the hybrid system is greatly unbalanced. With the two channels in this condition if a user of the substation apparatus speaks into the microphone 101, the signal currents resulting from the sound waves impinging upon the diaphragm of the microphone are amplified by the tandem connected amplifier units 108, 109 and 110 and are delivered through the coupling transformer 111 and the hybrid system 103 to the line terminating at the terminals 100. Due to the side tone suppressing action of the hybrid system 103 only a portion of these currents are transmitted through this system to the channel 106. If, however, the line conditions of the lines interconnecting the illustrated substation circuit with another distant substation are such that the hybrid system is substantially unbalanced the mag-

nitude of the signal currents passed to the input end of the channel 106 and transmitted through the amplifiers provided in this channel to the loud speaker 102 may be sufficient to cause the reproduction thereof at a substantial volume. The operation of the control circuit 143 obviates this difficulty. More particularly, the signal voltage impressed across the input electrodes of the amplifier tube 114 is also impressed across the input terminals of the amplifier 144. The amplified signal currents are transmitted through the coupling transformer 145 to the rectifying circuit including the dry disk rectifier 146. The arrangement is such that immediately a signal voltage is impressed upon this circuit the condenser 148 is quickly charged to build up a biasing voltage across the resistor 147 which bucks down the negative bias voltage normally impressed between the control electrodes of the direct current amplifier 149 by the battery 148, thus permitting anode current to traverse the output circuit of this amplifier, whereby a direct voltage is developed across the load resistor 150. The rectifier 146 is so poled that it only passes current of a polarity which will produce a positive biasing voltage between the input electrodes of the amplifier tube 149. The pulsations of this voltage are smoothed out by the action of the condenser 148.

The space current traversing the tube 149 and the load resistor 150 as a result of the signal voltage impressed upon the input electrodes of the amplifier 144 results in a voltage drop across the resistor 150 which is impressed as a positive biasing potential upon the control electrodes of the tubes 151 and 152 through the resistors 153 and 154, respectively. Thus, the negative bias normally impressed upon the indicated control electrodes by the batteries 155 and 156 is decreased to produce a substantial decrease in the output electrode impedances of these two tubes. As explained above, the decrease in the output electrode impedance of the tube 151 which shunts the shunt leg 131a of the voltage divider 131 results in a substantial decrease in the gain or signal current transmission efficiency of the channel 106. Conversely, the decrease in the output electrode impedance of the tube 152 which shunts the series leg 112a of the voltage divider 112, results in a substantial increase in the transmission efficiency of the channel 105 over which the signal currents are being transmitted from the microphone 101 to the line connected to the terminals 100. By proper selection and adjustment of the circuit elements involved, the transmission efficiency of the channel 106 may be decreased during use of the channel 105, to a point where no substantial reproduction of signal currents passed through the hybrid system 103 to the input side of the channel 106 occurs. The signal current transmission efficiencies of the two channels 105 and 106 are restored to normal in an obvious manner when the flow of signal currents over the channel 105 is terminated.

As explained previously, the control circuit 142 is identical in arrangement to the control circuit 143 and is provided for the purpose of controlling the transmission efficiencies of the two channels 105 and 106 during those intervals when signal currents are transmitted to the substation circuit over the line extending to the terminals 100. More particularly, the input terminals of the control circuit 142 are coupled to the channel 106 at a point immediately following the stage of amplification 129 through a resistance capacitance 75

network comprising a resistor 165 and a condenser 166. This circuit is provided with two control tubes corresponding to the tubes 151 and 152 of the control circuit 143. The output electrodes of one of the two tubes are bridged across the series leg 131a of the voltage divider 131 through a pair of low impedance direct current blocking condensers 167 and 168. The output electrodes of the other control tube embodied in the circuit 142 are bridged across the shunt leg 112a of the voltage divider 112 through a blocking condenser 169. With the control circuit 142 arranged in this manner it will be apparent from the preceding description with reference to the operation of the circuit 143 that when signal currents are delivered from the line extending to the terminals 100 through the hybrid system 103 to the channel 106 to cause the output electrode impedances of the tubes embodied in the control circuit 142 to be decreased, the transmission efficiency of the channel 105 is decreased and the transmission efficiency of the channel 106 is increased. Due to the decreased transmission efficiency of the channel 105, only a negligible portion of the sound energy is retransmitted through the acoustical coupling between the loud speaker 102 and the microphone 101, the channel 105 and the hybrid system 103 to the line terminating at the terminals 100.

By virtue of the particular arrangement of the transmission channels 105 and 106, the control circuits 142 and 143 and the hybrid system 103, it is possible for conversation break-ins to occur. Thus, if a user of the substation apparatus illustrated is speaking into the microphone 101 so that signal currents are being transmitted through the channel 105 and the hybrid system 103 to the line terminating at the terminals 100, the transmission channel 105 is operating with a high transmission efficiency, while the transmission efficiency of the channel 106 is quite low. Under these conditions if the party at the distant substation breaks in upon the conversation by causing signal currents to flow over the line terminating at the terminals 100 through the hybrid system 103 to the input side of the channel 106, the resulting operation of the control circuit 142 causes the transmission efficiency of the channel 105 to be lowered and the transmission efficiency of the channel 106 to be raised. More particularly, the signal currents incoming to the illustrated substation circuit are, by virtue of the arrangement of the hybrid system 103 transmitted with much greater efficiency to the input side of the channel 106 than are the signal currents transmitted through this system from the channel 105 to the channel 106 due to the unbalanced condition thereof. Accordingly, the magnitude of the incoming signal currents, when amplified by the amplifier unit 129 and impressed upon the input terminals of the control circuit 142, is sufficient to cause the output electrode impedances of the two control tubes embodied in this control circuit to be substantially reduced. In response to the reduction of these impedances the gain or transmission efficiency of the channel 105 is decreased and the transmission efficiency of the channel 106 is increased in the manner previously explained. Accordingly, a substantial portion of the signal currents incoming to the substation circuit are transmitted through the channel 106 to the loud speaker 102 for audible reproduction. Following the initial break-in, the person using the substation circuit illustrated is expected to stop speak-

ing. As a result, the control circuit 143 operates further to decrease the transmission efficiency of the channel 105 and further to increase the transmission efficiency of the channel 106 in a manner which will be clearly apparent from the foregoing explanation.

Referring now more particularly to Fig. 2 of the drawings, the substation circuit there illustrated is, in general, quite similar to that illustrated in Fig. 1 and described above. Briefly described, this circuit comprises a transmitter or microphone 201, receiving means in the form of a loud speaker 202, a hybrid system 203 including a line balancing network 204 and having line terminals 200, and two transmission channels 205 and 206 for coupling the microphone 201 and the loud speaker 202 to the hybrid system 203, respectively. The circuit further comprises two control circuits 242 and 243 which respectively correspond to the control circuits 142 and 143 illustrated in Fig. 1 and are provided for the purpose of controlling the transmission efficiencies of the two channels 205 and 206. The transmission channel 205 comprises a coupling transformer 207, an adjustable signal level controlling voltage divider 212, an amplifier tube 214 and a voltage transforming network 215 connected in tandem in the order named. The channel 206 similarly comprises a coupling transformer 228, an adjustable voltage divider 231, an amplifier tube 233, a voltage transforming circuit 235 and a coupling transformer 236 connected in tandem in the order named. More particularly, the input electrodes of the tube 214 are connected across the adjustable shunt leg 212b of the voltage divider 212 in series with a C battery 216 which is provided for biasing the control grid of the tube 214 to the proper negative potential with respect to the cathode of this tube. The output electrodes of the tube 214 are coupled to the outgoing signal current terminals of the hybrid system 203 through the voltage transforming circuit 215, which circuit comprises a pair of resistors 217 and 218 serially included in the channel and a third resistor 219 bridged across the channel. Screen and anode potentials are supplied to the tube 214 from a source of direct current, not shown, but having its positive terminal connected to the terminal marked +B, this source being by-passed for signal frequency currents by a condenser 220. The amplifier tube 233 included in the incoming signal current channel 206 comprises a pair of input electrodes which are bridged across the adjustable shunt portion 231b of the voltage divider 231 in series with a C battery 221 which functions to bias the control grid of this tube to the proper negative potential with respect to the cathode thereof. The output electrodes of the tube 233 are coupled through the voltage transforming circuit 235 to the primary winding of the transformer 236, a by-pass condenser 222 being provided for bypassing signal currents around the source of anode and screen potential which is connected to the terminal marked +B.

The two control circuits 242 and 243 are of identical arrangement and for this reason only the details of the control circuit 243 have been illustrated. In brief, this circuit comprises a pair of electron discharge tubes 251 and 252 arranged respectively to control the transmission efficiencies of the channels 206 and 205. More particularly, the output electrodes of the tube 251 are bridged across the shunt leg 231b of the voltage divider 231 through a low impedance 75

direct current blocking condenser 226 so that the transmission efficiency of the channel 206 is variable directly in accordance with changes in the output electrode impedance of this tube. 5 Similarly, the output electrodes of the tube 252 are bridged across the shunt leg 212b of the voltage divider 212 through a blocking condenser 227, whereby the signal transmission efficiency of the channel 205 is variable directly in accordance with the output electrode impedance of this tube. Anode potential is impressed upon the anode of the tube 252 over a path including the high impedance iron core choke coil 228 and a resistor 229. Similarly, anode potential is impressed 10 upon the anode of the tube 251 over a path including a high impedance iron core choke coil 232' and a resistor 233'. As in the arrangement illustrated in Fig. 1, the output electrode impedances of the tubes 251 and 252 are controlled by varying the potentials impressed upon the control electrodes thereof. To this end, there is provided a circuit which includes a transformer 260 having its primary winding bridged across the channel 205 and its secondary windings included in a rectifying circuit which also includes a pair of load resistors 261 and 262, the junction point of which is grounded, and a rectifier 263 which is preferably of the dry disk copper oxide type. The two series connected resistors 261 and 262 are bridged by a smoothing condenser 264 so that pulsating direct current developed in the rectifying circuit causes a reasonably smooth direct voltage to be developed across the two load resistors. The voltages developed across the resistors 261 and 262 during signal current transmission through the channel 205 are utilized to control the potentials impressed upon the control electrodes of the tubes 252 and 251, respectively. These electrodes are normally biased to the proper operating potentials through the provision of C batteries 265 and 266, respectively. More particularly, the tube 252 is normally negatively biased with a very low biasing voltage such that the output electrode impedance thereof is relatively low. The voltage of the battery 266, on the other hand, is such that the control tube 251 is normally negatively biased to a point closely approaching anode current cut-off, whereby the output electrode impedance of this tube is relatively high. With the rectifying circuit arranged in the manner illustrated, alternating signal currents traverse the rectifying circuit including the rectifier 263 and the resistors 262 and 261 in a clockwise direction such that the right terminal of the resistor 262 is rendered more positive to decrease the bias impressed upon the control electrode of the tube 251, and the left terminal of the resistor 261 is rendered more negative such that the bias is increased upon the control electrode of the tube 252. Thus, when signal currents traverse the channel 205 the output electrode impedance of the tube 251 is decreased and the output electrode impedance of the tube 252 is increased. The control circuit 243 further includes provisions for maintaining the signal output level of the channel 205 substantially constant regardless of changes in the amplitude of the signal input to the channel. More particularly, an automatic gain control circuit is provided for varying the output electrode impedance of the tube 252 inversely in accordance with the amplitude of signal currents impressed upon the input side of the channel 205. This automatic gain control circuit comprises a portion or all of the resistor 261, an auxiliary rectifier 269,

preferably of the dry disk copper oxide type, and a coupling path including a direct current blocking condenser 270 and a resistor 271.

As explained above, the control tubes 251 and 252 are normally biased to have high and low output electrode impedances respectively. Since the output electrode impedance of the tube 251 is bridged across the shunt leg 234b of the voltage divider 234 it will be apparent that the resistance of this shunt leg as combined with the output electrode impedance of the tube is relatively high corresponding to a relatively high transmission efficiency. On the other hand, the low output electrode impedance of the tube 252 which is connected to bridge the shunt leg 212b of the voltage divider 212 renders the transmission efficiency of the channel 205 relatively low for reasons which will be apparent from the foregoing explanation. By suitably adjusting the taps 213 and 232 any desired normal ratio between the transmission efficiencies of the two channels 205 and 206 may, within limits, be attained. With the apparatus at normal if a user of the substation circuit speaks into the microphone 201, the generated voice currents are transmitted through the coupling transformer 207, the voltage divider 212, the amplifier tube 214, the voltage transforming network 215 and the hybrid system 203 to the line extending to the terminals 200. If the hybrid system 203 is substantially unbalanced due to the conditions of the lines connected to the terminals 200, a substantial portion of the voice currents are transmitted through this system to the input side of the channel 206. In the absence of the control circuit 243 such currents would be amplified in the channel 206 and delivered to the loud speaker 202 for reproduction. The indicated control circuit, however, responds to the signal currents traversing the channel 205 by substantially decreasing the transmission efficiency of the channel 206 and substantially increasing the transmission efficiency of the channel 205. More particularly, a portion of the amplified signal currents are delivered through the coupling transformer 260 to the rectifying circuit including the rectifier 263, whereby biasing potentials are developed across the load resistors 261 and 262. The condenser 264 is initially charged at an extremely high rate so that the biasing potentials are available immediately speech transmission through the channel 205 is started. As previously explained, the voltage developed across the resistor 262 is poled so that the normal bias impressed upon the control electrode of the tube 251 is lowered, thereby to decrease the output impedance of this tube. Thus, the transmission efficiency of the channel 206 is decreased. Conversely, the voltage developed across the resistor 261 functions to increase the negative bias upon the control electrode of the tube 252 so that the output electrode impedance of this tube is increased to produce an increase in the transmission efficiency of the channel 205. The decreased efficiency of the channel 206 is such that no substantial reproduction of the signal currents delivered to the input side of this channel through the coupling afforded by unbalance in the hybrid system 203 occurs. As the speech transmission continues, the auxiliary circuit comprising the rectifier 269 functions to maintain the signal output level of the channel 205 substantially constant regardless of wide fluctuations in the intensity of the signal input to this channel. Thus, a portion of amplified signal voltage is impressed

by means of the condenser 270 and the resistor 271 upon the rectifying circuit which includes the rectifier 269 and the portion 261a of the resistor 261. The average amplitude of current traversing this rectifying circuit obviously varies directly in accordance with the average magnitude of the amplified signal currents. The rectifier 269 is so poled that the current traversing the auxiliary rectifying circuit is in opposition to the current traversing the primary rectifying circuit which includes the rectifier 263. Thus, the net voltage across the resistor 261 represents the difference between the voltage drops produced by the two currents. Since the current traversing the auxiliary rectifying circuit including the rectifier 269 tends to vary with the input signal intensity, this net voltage varies with signal amplitude to change the bias and thus alter the output electrode impedance of the tube 252. More particularly, when the signal input to the channel 205 is increased the currents traversing the auxiliary rectifying circuit tend to increase to produce a corresponding decrease in the bias on the control electrode of the tube 252 so that the output electrode impedance of this tube is decreased to lower the transmission efficiency of the channel 205 and thus decrease the amplitude of the signal current delivered to the auxiliary rectifying circuit. Conversely, a decrease in the signal input to the microphone 201 is accompanied by a decrease in the magnitude of the signal currents impressed upon the auxiliary rectifying circuit so that an increase occurs in the biasing voltage of the tube 252, whereby the output electrode impedance of this tube is increased to produce an increase in the transmission efficiency of the channel 205. Preferably, the characteristics of the auxiliary rectifier 269 are so chosen that the automatic gain control action just described is not started until the signal currents traversing the channel 205 reach an appreciable magnitude. If a rectifier of the copper oxide or dry disk type is used, this may be accomplished by varying the number of disks included therein, it being well understood in the art that the voltage-current characteristic of a rectifier of this type is substantially nonlinear and no substantial current flow therethrough occurs until a voltage of predetermined magnitude is impressed thereacross, but when this magnitude of voltage is exceeded the current rises steeply with increasing applied voltage. Hence, it will be understood that by varying the number of disks in the rectifier unit 269 no current flow through the circuit including this rectifier will occur to start the automatic gain control action until the signal transmission level reaches a desired value.

The level of signal transmission through the channel 205 is lowered somewhat by virtue of the inclusion of the voltage transforming circuit 215 in this channel. Thus, the net signal voltage impressed across the outgoing signal current terminals of the hybrid system 203 is the difference between the signal voltage impressed across the primary winding of the coupling transformer 260 and the signal voltage drops across the two series resistors 217 and 218 as determined by the value of the shunt resistor 219. The purpose of providing this voltage transforming circuit is that of substantially reducing the magnitude of signal currents transmitted to the rectifying circuit including the rectifier 263 through the coupling afforded by unbalance in the hybrid system 203 when signal currents are transmitted to the substation circuit from a distant substation. The

larger portion of signal currents incoming to the substation circuit over the associated line are transmitted through the hybrid system to the input side of the channel 206 and are delivered through the coupling transformer 228, the voltage divider 231, the amplifier tube 233, the voltage transforming circuit 235 and the coupling transformer 236 to the loud speaker 202 for reproduction. If the conditions of the connected lines respectively extending to the substation circuit illustrated and to the circuit of the distant substation are such that the hybrid system is considerably unbalanced, a substantial portion of the incoming signal currents may be transmitted through the hybrid system to the output side of the channel 205. Due to the above-described voltage reducing action of the circuit 215, however, these currents do not substantially affect the biasing voltages of the control tubes 251 and 252 even under the most unfavorable conditions of unbalance. The control circuit 242 responds to the signal currents transmitted thereto over the channel 206 by operating to lower the transmission efficiency of the channel 205 and to increase the transmission efficiency of the channel 206 in a manner identical with that just described with reference to the circuit 243. It will be noted that the input terminals of the control circuit 242 are coupled directly to the loud speaker 202, which speaker, being of the moving coil type, may function both as a transmitter and a receiver. Accordingly, sound waves impinging upon the diaphragm of this speaker cause signal voltages to be developed which are transmitted through the coupling transformer 236 and the voltage transforming circuit 235 to the input terminals of the control circuit 242. Due to the voltage reducing action of the circuit 235, however, the magnitude of such currents is so low as to cause no substantial response on the part of the control circuit 242.

The arrangement of Fig. 2, like that of Fig. 1, is such that signal current transmission in either direction may be interrupted to permit conversation break-ins. Thus, if incoming signal currents are being transmitted through the hybrid system 203 and the channel 206 to the loud speaker 202 and the user of the illustrated substation circuit desires to break in upon the speech train, he may do so by speaking into the microphone 201. The resulting signal currents are transmitted at low level through the voltage divider 212 to the input side of the amplifier 214 and following amplification through this tube are delivered through the coupling transformer 260 to the rectifying circuit including the rectifier 263. The resulting change in the output electrode impedance of the tubes 251 and 252 causes the transmission efficiency of the channel 206 to be lowered and the transmission efficiency of the channel 205 to be increased in the exact manner described above. The increase in the transmission efficiency of the channel 205 is such that the signal currents developed through operation of the microphone 201 are transmitted through this channel and the hybrid system 203 to the line connected to the terminals 200 with sufficient magnitude to cause the reproduction thereof by the receiving means provided at the distant substation. Conversation break-ins may also occur during those intervals when signal currents are being transmitted from the microphone 201 through the channel 205 and the hybrid system 203 to the line connected to the terminals 200. In the latter case the incoming signal currents 75

are transmitted through the hybrid system 203 to the channel 206 and the control circuit 242 responds thereto by operating to decrease the transmission efficiency of the channel 205 and to increase the transmission efficiency of the channel 206.

The arrangement illustrated in Fig. 3 of the drawings is substantially similar to that shown in Fig. 2 of the drawings and described above except that in the Fig. 3 arrangement the automatic gain control circuit has been omitted. Due to the similarity of the two circuits corresponding elements thereof have been identified by reference characters having the same tens and units digits, but different hundreds digits respectively corresponding to the figure numbers. The primary difference in the two circuits resides in the arrangement of the rectifying circuit through operation of which the output electrode impedances of the two control tubes are controlled in magnitude. In the Fig. 3 arrangement the rectifying circuit includes a single resistor 361 which is shunted by a condenser 364 and connected in circuit with a rectifier 363 and the secondary winding of the coupling transformer 360, the junction point between the lower terminal of the secondary transformer winding and the upper pole of the rectifier 363 being grounded in the manner shown. With this arrangement, the voltage drop across the rectifier 363 functions as the voltage for controlling the bias potentials of the two control tubes 351 and 352, the rectifier 363 being so poled that an increased negative bias is impressed upon the indicated control electrodes when signal currents traverse the channel 305. This particular arrangement of the rectifying circuit is well adapted to the use of a vacuum tube diode as the rectifying element. Since, however, only a single control voltage of one polarity is available the circuit is arranged so that the output electrode impedances of the two control tubes 351 and 352 are changed in the same sense when a bias voltage is developed as a result of signal currents traversing the channel 305. Accordingly, the output electrodes of the tube 351, which functions to control the transmission efficiency of the channel 306, are coupled to the series leg 331_a of the voltage divider 331 so that when the output electrode impedance of the tube is increased the transmission efficiency of the channel 306 is decreased and vice versa. Since the two terminals of the series leg 331_a are both above ground potential, a coupling transformer 374 is utilized to couple the output electrodes of the tube 351 across this leg of the voltage divider. The output electrodes of the tube 352, which is provided to control the transmission efficiency of the channel 305, are bridged across the shunt leg 312_b of the voltage divider 312 through the blocking condenser 327. The voltages of the two C batteries 365 and 366 are such that very low bias voltages are normally impressed upon the control electrodes of the two tubes 351 and 352. This, of course, means that the output electrode impedance of each of the two tubes is relatively low. With the output electrode impedance of the tube 351 at a low value, the transmission efficiency of the channel 306, as determined by the control action of the tube 351, is relatively high. Conversely, with the output electrode impedance of the tube 352 at a low value, the transmission efficiency of the channel 305, as determined by the control action of this tube, is relatively low. By proper adjust-

ment of the taps 313 and 332 the indicated transmission efficiencies of the two channels may be adjusted to any desired normal ratio. With the apparatus at normal if sound waves impinge upon the diaphragm of the microphone 301, the resulting signal currents are transmitted through the transformer 307, the voltage divider 312 and the tube 314 to the coupling transformer 360, thereby to cause rectified signal currents to traverse the rectifying circuit including the rectifier 363. The voltage developed across the rectifier 363 increases the negative bias upon the control electrodes of each of the two tubes 351 and 352, thereby to cause the output electrode impedances of these two tubes to be increased. As a result, the transmission efficiency of the channel 305 is increased and the transmission efficiency of the channel 306 is decreased in a manner which will be clearly apparent from the foregoing explanation. Aside from the differences noted, the mode of operation of the circuit arrangement illustrated in Fig. 3 is exactly the same as that described above with reference to the arrangement illustrated in Fig. 2, it being noted, however, that no automatic gain control action is provided in the Fig. 3 arrangement.

While there have been described what are at present considered to be the preferred embodiments of the invention, it will be understood that various modifications may be made therein, and it is contemplated to cover in the appended claims all such modifications as fall within the true spirit and scope of the invention.

What is claimed is:

1. In a transmission system, a pair of channels for transmitting signal currents in different directions, means providing coupling between said channels, a voltage divider included in each of said channels, each of said voltage dividers including a series leg and a shunt leg, a pair of electron discharge tubes each including an input electrode and including output electrodes respectively bridged across the shunt legs of said voltage dividers, whereby the signal current transmission efficiencies of said channels are respectively variable directly in accordance with the output electrode impedances of the respective associated tubes, means for impressing biasing potentials upon said control electrodes, a control circuit coupled to said one channel at one point and including signal voltage rectifying means and circuit elements for impressing the rectified signal voltages upon said control electrodes to vary the potentials thereof in opposite senses such that the output electrode impedance of the tube associated with said one channel is increased and the output electrode impedance of the tube associated with said other channel is decreased when signal currents traverse said one channel, and means comprising a voltage transforming circuit included in said one channel at a point between said one point and said coupling means for preventing signal currents transmitted through said other channel and fed through said coupling means to said one channel from substantially changing said potentials.

2. In a transmission system, a pair of channels for transmitting signal currents in different directions, an electron discharge tube including a control electrode and a pair of output electrodes coupled to one of said channels, a second electron discharge device including a control electrode and a pair of output electrodes coupled to the other of said channels, the output electrode im-

pedances of said tubes being variable in accordance with changes in the potentials impressed upon the control electrodes thereof to vary the signal current transmission efficiencies of the 5 respective associated channels, means responsive to signal currents traversing said one channel for varying the potentials upon said control electrodes to increase the signal current transmission efficiency of said one channel and to decrease 10 the signal current transmission efficiency of said other channel, and means including one of said tubes for varying the signal current transmission efficiency of said one channel inversely in accordance with the amplitude of the signal input thereto.

3. In a transmission system, a pair of channels for transmitting signal currents in different directions, an electron discharge tube including a control electrode and a pair of output electrodes 20 coupled to one of said channels, a second electron discharge device including a control electrode and a pair of output electrodes coupled to the other of said channels, the output electrode impedances of said tubes being variable in accordance with changes in the potentials impressed upon the control electrodes thereof to vary the signal current transmission efficiencies of the 25 respective associated channels, means responsive to signal currents traversing said one channel for varying the potentials upon said control electrodes to increase the signal current transmission efficiency of said one channel and to decrease the signal current transmission efficiency of said other channel, and means controlled in 30 accordance with the amplitude of signal currents traversing said one channel for further controlling the output electrode impedance of the tube associated with said one channel to vary the signal current transmission efficiency of said one channel inversely in accordance with the amplitude of the signal input thereto.

4. In a transmission system, a signal current transmission channel, an electron discharge tube including a pair of output electrodes, means for 45 coupling said output electrodes to said channel so that the signal current transmission efficiency of said channel is changed in one sense in response to an increase in the output electrode impedance of said tube and is changed in an opposite sense in response to a decrease in the output electrode impedance of said tube, means responsive to signal currents traversing said channel for changing the output electrode impedance of said tube substantially to increase the signal current transmission efficiency of said one channel, and means controlled in accordance with the amplitude of signal currents traversing said channel for further controlling the output electrode impedance of said tube to vary the signal current transmission efficiency of said channel inversely in accordance with the amplitude of the signal input thereto.

5. In a transmission system, a signal current transmission channel, an electron discharge tube including a pair of output electrodes and a control electrode for changing the impedance across 65 said output electrodes, means for coupling said output electrodes to said channel so that the signal current transmission efficiency of said channel is changed in one sense in response to an increase in the output electrode impedance of said tube and is changed in an opposite sense in response to a decrease in the output electrode impedance of said tube, means for impressing a 70 biasing potential upon said control electrode,

means responsive to signal currents traversing said channel for changing said potential in a direction substantially to increase the signal current transmission efficiency of said channel, and means controlled in accordance with the amplitude of signal currents traversing said channel for further controlling said potential to vary the signal current transmission efficiency of said channel inversely in accordance with the amplitude of the signal input thereto.

6. In a transmission system, a signal current transmission channel, an electron discharge tube including a pair of output electrodes and a control electrode for changing the impedance across said output electrodes, means for coupling said output electrodes to said channel so that the signal current transmission efficiency of said channel is changed in one sense in response to an increase in the output electrode impedance of said tube and is changed in an opposite sense in response to a decrease in the output electrode impedance of said tube, means for impressing a biasing potential upon said control electrode, a control circuit coupled to said one channel and including signal voltage rectifying means and a circuit element for impressing the rectified signal voltage upon said control electrode to vary the potential of said control electrode in a direction substantially to increase the signal current transmission efficiency of said channel when signal currents traverse said channel, and a second control circuit including at least a portion of said circuit element and additional rectifying means for further controlling said potential to vary the signal current transmission efficiency of said channel inversely in accordance with the amplitude of the signal input thereto.

7. In a transmission system, a pair of channels for transmitting signal currents in different directions, a voltage divider included in each of said channels, each of said dividers including a series leg and a shunt leg, a pair of electron discharge tubes each including an input electrode and including output electrodes respectively bridged across the shunt legs of said voltage dividers, whereby the signal current transmission efficiencies of said channels are respectively variable directly in accordance with the output electrode impedances of the respective associated tubes, means for impressing biasing potentials upon said control electrodes, means responsive to signal currents traversing one of said channels for varying said potentials in opposite senses such that the output electrode impedance of the tube associated with said one channel is increased and the output electrode impedance of the tube associated with said other channel is decreased, and means controlled in accordance with the amplitude of signal currents traversing said one channel for further controlling the output electrode impedance of the tube associated with said one channel to vary the signal current transmission efficiency of said one channel inversely in accordance with the amplitude of the signal input thereto.

8. In a transmission system, a signal current transmission channel, a voltage divider comprising a leg serially included in said channel and a leg shunting a portion of said channel, an electron discharge tube including a pair of output electrodes bridged across one of said legs, whereby the signal current transmission efficiency of said channel is changed in one sense in response to an increase in the output electrode impedance

of said tube and is changed in the opposite sense in response to a decrease in the output electrode impedance of said tube, means responsive to signal currents traversing said channel for changing said impedance in a direction substantially to increase the signal current transmission efficiency of said channel, and means controlled in accordance with the amplitude of signal currents traversing said channel for further controlling said impedance to vary the signal current transmission efficiency of said channel inversely in accordance with the amplitude of the signal input thereto.

9. Telephone substation apparatus comprising transmitting means, receiving means and a hybrid system adapted to be connected to a line extending to said apparatus, a normally active channel for transmitting signal currents from said transmitting means to said hybrid system, a second normally active channel for transmitting signal currents from said hybrid system to said receiving means, a voltage divider included in each of said channels, each of said dividers including a leg serially included in the associated channel and a leg shunting a portion of the associated channel, an electron discharge tube including output electrodes bridged across one leg of the divider included in one of said channels so that the signal current transmission efficiency of said one channel is determined by the impedance across said electrodes, a second electron discharge tube including output electrodes bridged across one leg of the voltage divider included in the other of said channels so that the signal current transmission efficiency of said other channel is determined by the impedance across said last-named electrodes, means responsive to signal currents traversing said one channel for varying the output electrode impedances of said tubes substantially to increase the signal current transmission efficiency of said one channel and substantially to decrease the signal current transmission efficiency of said other channel, and means controlled in accordance with the amplitude of signal currents traversing said one channel for changing the output electrode impedance of said first-named tube to vary the signal current transmission efficiency of said one channel inversely in accordance with the amplitude of the signal input thereto.

10. In a transmission system, a signal current transmission channel, an electron discharge tube including a pair of output electrodes and a control electrode for changing the impedance across said output electrodes, means coupling said output electrodes to said channel so that the transmission efficiency of said channel is varied directly in accordance with the output electrode impedance of said tube, a biasing resistor connected in circuit with said control electrode, rectifier means coupled to said channel and operative to build up a bias voltage across said resistor of the correct polarity to increase the output electrode impedance of said tube when signal currents traverse said channel, and additional rectifier means coupled to said channel and operative to build up an opposing voltage across at least a portion of said resistor which varies directly in accordance with the amplitude of the signal input to said channel, whereby the transmission efficiency of said channel is varied inversely in accordance with the amplitude of the signal input thereto.

ROSWELL H. HERRICK.
